Int. Cl. E01b 27/17**U.S. Cl. 104—12****1 Claim****ABSTRACT OF THE DISCLOSURE**

There is provided a method and apparatus for levelling railroad track to improve the packing of ballast under the ties of the track. The improvement comprises determining the weight of the track carried by the ballast at a point in the track and continuing to pack ballast under the tie at that point until substantially all the weight of the track at that point is carried by the ballast.

BACKGROUND OF THE INVENTION

This invention relates to apparatus for levelling railroad track, that is apparatus for detecting and correcting vertical errors of alignment in railroad track comprising rails secured to ties.

Apparatus for levelling railroad track usually comprises detection means for determining the vertical error at a point on the track, means for lifting the track to correct the vertical error and tamping means for packing ballast underneath the tie at that point to support the track and to maintain the track at the corrected vertical position. The track is usually checked for vertical positioning at every tie therealong. It will be seen, therefore, that to achieve a reasonable rate of track correction the time occupied in checking the track at each tie should be as short as possible. At the present time track levelling apparatus has included a time delay relay which has allowed the tamping means to operate for a certain period of time in the packing operation. After the predetermined period of time the apparatus is moved on to the next point in the track to be corrected. It has been found that such track levelling apparatus does not always result in properly levelled tracks. It has been found that this is due to a scarcity of ballast at some of the ties in the track. Thus, when the predetermined period of time for operation of the tamping means has expired, the tamping means have not been able to find sufficient ballast to pack under the tie to take all the weight of the track so that on release of the track lifting means the track has subsided beyond its required vertical position.

SUMMARY OF THE INVENTION

It is an object of the present invention to provide improved track levelling apparatus and an improved method of levelling railroad tracks.

It is a further object of the invention to provide an apparatus and a method which determines that a tie at a particular point at which the track is being levelled is fully supported by ballast at the end of the levelling operation at that point.

According to the invention, there is provided in a method of levelling railroad track such as described above the improvement comprising determining the weight of the track carried by the ballast at a particular point being levelled and continuing to pack ballast under the tie at that point until substantially all the weight of the track at that point is carried by the ballast.

The invention provides apparatus for levelling railroad track including the combination of detection means for determining a vertical error in the track at a point therein, lifting means for the track at that point, said lifting means being controlled by the detection means to lift the track

2

sufficiently to correct the vertical error, tamping means for packing the ballast under a tie at that point to support the track in its correct vertical position, and control means associated with the lifting means for determining the weight of the track carried by ballast under the tie.

BRIEF DESCRIPTION OF THE DRAWINGS

An embodiment of the invention will now be described by way of example in conjunction with the accompanying drawings which is a somewhat diagrammatic representation of part of a track levelling apparatus showing the features of the invention.

DESCRIPTION OF THE PREFERRED EMBODIMENT

The drawing shows diagrammatically one side only of track levelling apparatus having a main frame 1 which carries wheels 2 running on a track comprising rails 3 (only one of which is shown) secured to ties 4 (only one of which is shown) which rest on a bed of ballast 5.

Secured to the forward end of the frame 1 of the apparatus is tamping means shown generally at 6 and comprising a frame 7 secured to the frame 1 and having tamping heads 8 mounted thereon for movement vertically with respect to the track and for movement towards and away from a tie 4 in a manner generally known. Similarly, the lifting means shown in the drawings are generally known. Such lifting means comprise a hydraulic piston and cylinder assembly 9 having a foot 10 connected to a piston rod 11, the foot 10 being adapted to extend to the ballast 5. The cylinder 12 of the assembly 9 is connected to the frame 1. Also connected to the frame 1 is a lifting hook 13 which has claws 14 for gripping on either side of a rail 3. As is known in the art, on pressurization of the cylinder assembly 9 the foot 10 can extend into contact with the ballast 5 and the hook 13 grips a rail. Continued pressurization of the assembly 9 causes the piston rod 11 to extend lifting the frame 1 and the rail 3.

The control apparatus is of a conventional type comprising a track level detector 15 which may be of the wire controlled type or of the light beam controlled type, a lift control 16 which controls the flow of pressurized hydraulic fluid along a conduit 17 to the assembly 9 by means of a valve 17a to lift the rail 3 as required by the detector 15, and a tamping means control 18 which is brought into operation to have the tamping heads 8 pack ballast under a tie 4 when the track level detector 15 has determined that the track has been lifted the required amount.

In accordance with the present embodiment of the invention, a pressure transducer 19 is located in the cylinder 12 of the assembly 9. The transducer 19 is connected to a relay 20 which provides overriding control on the tamping means. The transducer relay contacts are maintained in a closed position by any pressure over a predetermined minimum pressure in the cylinder 12. When the contacts in relay 20 are closed, an actuation signal is given to the tamping control 18. This signal from the relay 20 of course only actuates the tamping heads after the initial signal has been given by the lift control 16.

In operation, the apparatus is moved along the track to a point at which the determination of track level is to take place. The apparatus is stopped and the track level detector 15 is actuated to determine whether there are errors in the track level at that point by reference to a datum which may be in the form of a reference beam or a wire. Should the track level detector determine that there is a vertical error in the track, it actuates the lift control 16 to place the foot 10 of the hydraulic cylinder assembly 9 on the ballast 5 and to place the gripping means 14 of the lifting hook 13 about the rail 3. Increased pressure is applied to the cylinder 12 to lift the rail 3 and the apparatus thereon

until the track level detector 15 indicates that the rail is at the correct vertical position. The hydraulic line 27 to the cylinder 12 is then closed and the tamping control 18 actuated to operate the tamping heads 8 to pack ballast under the tie 4. The pressure in the cylinder 12 has meanwhile acted upon the transducer 19 to close the contacts in the transducer relay 20 to pass a signal to the tamping control 18. This signal maintains the tamping heads in operation and is in effect as long as the transducer relay contacts are closed. As ballast is packed under the tie, the ballast takes an increasing portion of the weight of the tie, then the contacts of the relay 20 will be removed from the piston and cylinder assembly 9. When substantially the whole of the weight of the track is taken by the tie 4, the pressure in the cylinder assembly 9 reduces to below the aforesaid predetermined value opening the contacts of the relay 20 deactivating the tamping control 18 and stopping the operation of the tamping heads 8.

Should there be insufficient ballast in the proximity of the tie 4 to be transferred under the tie 4 to take the weight of the tie, then the contacts of the relay 20 will remain closed. In this event, it will become apparent, by continued operation of the tamping heads, to the operator that there is an insufficiency of ballast and he can then remedy the situation by supplying additional ballast.

When the pressure in the cylinder 12 has reduced to substantially zero and the contacts of the relay 20 have opened, the rail 3 is at its correct position and will not subside on release of the lifting means. When the contacts of the relay 20 open, the levelling cycle is terminated

and the apparatus is moved on to the next point on the track at which levelling is to take place.

What I claim as my invention is:

1. In apparatus for levelling railroad track, the combination of: detection means for determining a vertical error in the track at a point therein; a hydraulic piston and cylinder assembly for lifting the track at that point, said lifting assembly being controlled by the detection means to lift the track sufficiently to correct the vertical error; tamping means for packing ballast under a tie at that point to support the track in its correct vertical position, and control means including a pressure transducer for determining when the said tie is taking the weight of the track by determining a reduction in pressure in said assembly and said control means being operatively connected to said tamping means to cause a repeat operation of the tamping means until said transducer determines that the pressure in said assembly is below a predetermined value.
